PENICILLIN SALTS OF METHYL-PENTYLAMINE

Vernon V. Young, Terre Haute, Ind., assignor to
 Commercial Solvents Corporation, Terre Haute,
 Ind., a corporation of Maryland

No Drawing. Application February 3, 1950,
 Serial No. 142,355

4 Claims. (Cl. 260—239.1)

1

This invention relates to salts of penicillin and more particularly relates to the penicillin salt of three isomers of (methylpentyl) amine.

All penicillin salts are not practical for therapeutic use. For example, a penicillin salt may not be stable at ordinary temperatures and thus in order for the therapeutic activity of the salt to be retained, it must be refrigerated during storage or else rapid deterioration of the therapeutic activity occurs. Some penicillin salts are too toxic for use therapeutically and hence must be ruled out completely.

In addition to the stability and toxicity characteristics of penicillin salts consideration must also be given to their solubility properties. The expression of favorable solubility properties is found in the measurement of blood levels of the penicillin at intervals after injection into or ingestion by the body. The longer penicillin can be found in the blood after it has been placed in the body, the more effective it is against pathogenic organisms present in the body provided they are penicillin susceptible. If, however, higher blood levels of penicillin are only maintained for short periods after injection or ingestion of the penicillin salt, the penicillin content of the salt is largely wasted and there is little or no alleviation of the pathologic condition being treated unless there are repeated administrations of the penicillin at short intervals.

The object of the present invention is to provide stable penicillin salt compositions of low toxicity which give prolonged blood levels of penicillin whether given orally or by injection.

I have now discovered stable penicillin salts possessing low toxicity characteristics which give prolonged blood levels after being injected into the body or after being administered orally. My new compositions are the penicillin salts of the isomers (1 - methylpentyl) amine, (2 - methylpentyl) amine, and (1-methylisopentyl) amine.

My new compositions can be prepared by mixing one equivalent of a water-soluble penicillin salt such as potassium penicillin in aqueous solution with one equivalent of (1-methylpentyl)-amine hydrochloride, (2-methylpentyl) amine hydrochloride or (1-methylisopentyl) amine hydrochloride as the case may be in aqueous solution. The penicillin salt precipitated from the aqueous solution is recovered therefrom by filtration and

2

dried. (Penicillin salt of (1-methylpentyl) amine: Nitrogen analysis—Calc. 9.65; found 9.36. Penicillin salt of (2-methylpentyl) amine: Nitrogen analysis—Calc. 9.65; found 9.31. Penicillin salt of (1-methylisopentyl) amine: Nitrogen analysis—Calc. 9.65; found 9.26.)

Blood level tests were conducted wherein my new penicillin salts of (1-methylpentyl) amine, (2 - methylpentyl) amine, and (1 - methylisopentyl) amine were given orally, and injected intramuscularly into dogs, the amount of penicillin in the blood stream being measured at definite intervals after administration. The following table shows the blood levels obtained after a portion of my new penicillin salt of (1-methylpentyl) amine containing 100,000 units of penicillin was administered orally.

Table I

[Penicillin salt of (1-methylpentyl)amine; oral administration—100,000 units/dog; units penicillin/ml. blood.]

Dog No.	Hours					Remarks
	0	2	4	6	8	
25						
76	0	.750	.190	.081	.050	Tablet.
77	0	.750	.185	.038	0	Do.
57	0	.820	.300	.074	0	Do.
44	0	1.75	.380	.069	0	Do.
45	0	1.00	.620	.140	0	Do.
62	0	.725	.274	.147	0	Do.
30						

The following table indicates blood levels obtained when my new penicillin salt of (2-methylpentyl) amine was administered orally, 100,000 units of penicillin being administered to each dog.

Table II

[Penicillin salt of (2-methylpentyl)amine; oral administration—100,000 units/dog; units penicillin/ml. blood.]

Dog No.	Hours					Remarks
	0	2	4	6	8	
31	0	1.26	.190	.059	.058	Tablet.
57	0	1.98	.280	.126	0	Do.
31	0	.60	.157	.095	.056	Do.
57	0	.610	.114	.106	.039	Do.
38	0	.540	.227	.060	0	Do.
32	0	.675	.227	.093	.048	Do.
51	0	1.00	.290	.112	.052	Do.

50 The following table is offered for comparison

purposes. It shows blood levels obtained when procaine penicillin was administered orally, 100,000 units of penicillin being administered to each dog. Procaine penicillin is presently accepted as being the best form of the antibiotic.

Table III

[Procaine penicillin; oral administration—100,000 units/dog; units penicillin/ml. blood.]

Dog No.	Hours					Remarks
	0	2	4	6	8	
31	0	0.178		0	0	Tablet.
57	0	0.480		0.140	0.031	Do.
79	0	0.790	0.029	0.068	0	Do.
31	0	0.180	0.024	0	0	Do.
57	0	1.98	0.480	0.106	0	Do.
77	0	0.710	0.191	0.112	0.109	Do.

It can be seen from a comparison of the tables giving data on blood levels obtained after oral administration of the various salts of penicillin, that my new compounds give more consistent blood levels than the present best known form of penicillin.

The following table indicates blood levels obtained when my new penicillin salt of (1-methylpentyl)amine was injected intramuscularly as a suspension in peanut oil, 60,000 units of penicillin being injected into the dog.

Table IV

[(1-methylpentyl)amine; intramuscularly—oil suspension—60,000 units/dog; units penicillin/ml. blood.]

Dog No.	Hours				Remarks
	0	12	24	48	
45	0	—	0.082	0	

The following table indicates blood levels obtained when my new penicillin salt of (1-methylisopentyl)amine was injected intramuscularly as a suspension in peanut oil, 60,000 units of penicillin being injected into each dog.

Table V

[(1-methylisopentyl) amine; intramuscularly—oil suspension—60,000 units/dog; units penicillin/ml. blood.]

Dog No.	Hours						Remarks
	0	6	12	24	36	48	
76	0	.700	.163	.200	.108	.072	
77	0	.440	.079	.049	0	0	

The following table is offered for comparison purposes also. It shows blood levels obtained when procaine penicillin was administered intramuscularly as a suspension in peanut oil, 60,000 units of penicillin being injected into each dog.

Table VI

[Procaine penicillin; intramuscularly—oil suspension—60,000 units/dog; units penicillin/ml. blood.]

Dog No.	Hours			Remarks
	0	24	48	
79	0	0.024	0	
49	0	0.033	0	
32	0	0	0	
53	0	0.210	0	

It can be seen from a comparison of Tables IV, V, and VI that my new compounds give longer and more consistent blood levels when administered as a suspension in oil than the presently considered best known form of the antibiotic.

The following table indicates blood levels obtained when my new penicillin salt of (2-methylpentyl)amine was injected intramuscularly as an aqueous suspension, 60,000 units of penicillin being injected into each dog.

Table VII

[(2-methylpentyl)amine; intramuscularly—aqueous suspension—60,000 units/dog; units penicillin/ml. blood.]

Dog No.	Hours			
	0	1	2	6
77	0	2.57	0.220	0
78	0	3.80	1.23	0

The following table indicates blood levels obtained when my new penicillin salt of (1-methylisopentyl)amine was injected intramuscularly as an aqueous suspension, 60,000 units of penicillin being injected into each dog.

Table VIII

[(1-methylisopentyl)amine; intramuscularly—aqueous suspension—60,000 units/dog; units penicillin/ml. blood.]

Dog No.	Hours			
	0	2	6	12
77	0	2.05	.084	0
78	0	1.09	.100	0

The following table shows the results of toxicity tests upon the new penicillin salt of (1-methylpentyl)amine conducted on laboratory mice. The table shows the amount of my new compound which can be administered without any mouse fatalities, the amount given to produce a 50% kill of the mice tested, and the amount required to give a 100% kill of the mice tested. The penicillin salt was injected intraperitoneally and subcutaneously as indicated in the table.

Table IX

[Toxicity—(1-methylpentyl)amine.]

	LD ₀	LD ₅₀	LD ₁₀₀	mg. of salt/kg. of body weight of test mice	
				Intraperitoneally	Subcutaneously
	50	260±20	400		
	200	860	1,600		

The following table shows results of toxicity tests of my new penicillin salt of (2-methylpentyl)amine, the tests having been conducted on mice as shown above for Table IX.

Table X

[Toxicity—(2-methylpentyl)amine.]

	LD ₀	LD ₅₀	LD ₁₀₀	mg. of salt/kg. of body weight of test mice	
				Intraperitoneally	Subcutaneously
	250	480±43	800		
	200	810±143	1,600		

The following table shows results of toxicity tests of my new penicillin salt of (1-methyliso-

pentyl)amine.

5

pentyl) amine, the tests having been conducted on mice as shown above for Tables IX and X.

Table XI

[Toxicity—(1-methylisopentyl)amine.]

	LD ₀	LD ₅₀	LD ₁₀₀
mg. of salt/kg. of body weight of test mice			
Intraperitoneally.....	250	>550	>550
Subcutaneously.....	>1,600	>1,600	>1,600

The following table shows results of toxicity tests of procaine penicillin, the tests having been conducted on mice as shown above for Tables IX and XI.

Table XII

[Toxicity—procaine.]

	LD ₀	LD ₅₀	LD ₁₀₀
mg. of salt/kg. of body weight of test mice			
Intraperitoneally.....	200	440±28	>550
Subcutaneously.....	1,600	>1,600	>1,600

From the above 12 tables it can be seen that my new compounds are distinct improvements over procaine penicillin which is considered to be the

6

best form of penicillin presently available to the trade.

My new compounds are therapeutically effective veterinary compounds and they are useful in treating diseases in animals caused by penicillin susceptible organisms.

Now having disclosed my invention what I claim is:

10 1. The penicillin salt of a compound selected from the group consisting of (1-methylpentyl)-amine, (2-methylpentyl) amine, and (1-methylisopentyl) amine.

2. The penicillin salt of (1-methylpentyl)-amine.

15 3. The penicillin salt of (2-methylpentyl)-amine.

4. The penicillin salt of (1-methylisopentyl)-amine.

VERNON V. YOUNG.
